UNITED STATES PATENT OFFICE

2,092,020

NECKTIE

Benedict Ray, San Juan, P. R.

Application March 12, 1937, Serial No. 130,457

2 Claims. (Cl. 2—145)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates generally to an improved design for neckties, but more particularly to a necktie provided with an attaching means formed integral therewith.

10 One object of the invention is to provide a necktie devoid of surplus material, which may be worn particularly with uniforms, where long extending ends, are not only unnecessary, but bunglesome, and prevent a smooth fit of the coat.

15 Another object of the invention is to provide a simple and effective attaching means formed integral with the tie, which engages with a shirt button to hold the necktie in proper position.

20 With these and other objects in view this invention consists in certain novel details of construction, combination and arrangement of parts to be more fully hereinafter described and set forth in the accompanying claims.

25 In the accompanying drawing wherein the preferred embodiment of the invention is shown—

Fig. 1 is a view showing in full lines the front face of necktie and the portion of the folded extremity constituting the laterally extending tab;

Fig. 2 shows the rear face of the necktie and the entire folded extremity; and

30 Fig. 3 is a view showing the necktie in tied position with its laterally extending flap in engagement with a shirt button.

The necktie shown is of the four-in-hand type and may be any well known construction. It is provided with a central body portion or neck band (1), a large outer end or apron (2), and a smaller inner end (3), which may be tapered to a greater width than the neck band, or of the same width throughout as shown in the illustrations.

40 The apron (2) terminates in a diagonal edge (4), and the end portion adjacent this extremity is folded back along the line (5), and sewed to

the rear face of the apron (2) to form a hem.

By thus hemming the extremity of the apron (2) a projecting tab (6) is formed into which a buttonhole (7) is worked. The edge (4) of this hem may be seamed only along the extent of the tab, as from (8) to (9) and the remainder of edge (9) to (10) stitched to the rear face of the apron (2), or the entire edge (4) may be first seamed and then the portion (9) to (10) in contact with the rear face of the apron (2) sewed 10 to the latter.

The apron (2), is preferably made much shorter than those of the ordinary necktie, since it is primarily intended to be used with a uniform coat which always remains buttoned, and therefore it is only necessary for the necktie to extend a short distance below the folded edge of the lapels.

Although in the foregoing, various elements have been defined as best adapted to perform 20 the functions allotted to them, nevertheless it is to be understood that various minor changes may be resorted to within the scope of the appended claims, without departing from or sacrificing any of the principles of this invention.

25 Having described my invention, what I claim as new and wish to secure by Letters Patent is:

1. A necktie comprising a neck-band, an inner end, and an apron terminating in a diagonal edge, said apron being folded upon itself adjacent said edge to form a hem, and a tab, formed by the laterally projecting portion of said hem, provided with a buttonhole adapted to engage a button of a shirt.

2. A necktie comprising a neck-band, an inner 35 end, and an apron terminating in a diagonal edge, said apron being folded upon itself adjacent said edge to form a hem, and a tab, formed by the laterally projecting portion of said hem seamed along said diagonal edge and provided with a buttonhole adapted to engage the button of a shirt.

BENEDICT RAY.
